UNITED STATES PATENT OFFICE.

LOUIS ALLEN MAYO, OF CLIFTON HILL, MISSOURI.

ADJUSTABLE BOOK-SUPPORT.

SPECIFICATION forming part of Letters Patent No. 621,357, dated March 21, 1899.

Application filed May 21, 1898. Serial No. 681,316. (No model.)

To all whom it may concern:

Be it known that I, LOUIS ALLEN MAYO, a citizen of the United States, residing at Clifton Hill, in the county of Randolph and State 5 of Missouri, have invented a new and useful Adjustable Book-Support, of which the following is a specification.

My invention is in the nature of an improved adjustable and revoluble desk, stand, 10 or support for heavy books.

The object of my invention is to provide an adjustable book-support especially intended to be screwed or bolted to a hotel-counter to support the register, although equally applicable for use by commercial houses, banks, 15 record-offices, and similar establishments for conveniently holding and manipulating ledgers, records, or other heavy books the position of which it is desirable to change frequently 20 for reference thereto or making entries and rulings therein.

With this object in view my invention consists in an adjustable book-support comprising a base adapted to be screwed or bolted to 25 a counter, table, or desk, a pedestal revolvably mounted thereon and provided with a head or top supplied with radiating arms, preferably four, lugs projecting upward from two of said arms diametrically opposite each 30 other, a frame pivotally mounted in said lugs in a manner to permit of its tilting, adjusting devices secured to the other two diametrically opposite arms to secure the tilting frame in position, and extensible rods at one end of 35 the tilting frame provided with means for securing various sizes of books thereupon.

My invention further consists in the improved construction, arrangement, and combination of parts hereinafter fully described 40 and afterward particularly pointed out in the claims.

In order to enable others skilled in the art to which my invention most nearly appertains to make and use the same, I will now proceed to 45 describe its construction and operation, having reference to the accompanying drawings, forming part hereof, in which—

Figure 1 is a perspective view illustrating a book - support constructed in accordance 50 with my invention. Fig. 2 is a vertical sectional view of the same, taken on a plane cut through from front to rear. Fig. 3 is a detail

sectional view illustrating the manner of mounting the extensible book-securing rods.

Like letters of reference indicate the same 55 parts in all the figures of the drawings.

Referring to the drawings by letters, A indicates a flat base adapted to be secured to a counter, desk, or table by screws, bolts, or other suitable means. Centrally through it 60 is an opening square in outline and of two diameters, the larger diameter being adapted to receive the square head B of a square bar C, while the smaller diameter fits the bar itself. Upon this square bar is fitted a bushing 65 D, upon which a hollow pedestal E is mounted to turn, said pedestal being provided with a circular base F, threaded upon its lower end, bearing-balls G being inserted in opposing grooves in the upper surface of the 70 base A and under surface of pedestal-base F.

H indicates a top or head secured to the upper end of the pedestal, provided with a concentric vertical flange I, having a screw-thread on its outer surface.

75

J indicates a head somewhat similar in shape to the lower head F of the pedestal, but reversed in position and resting upon bearing-balls K in opposing grooves in its lower surface and the upper surface of the top or 80 head H. This head J is held down by a nut L, threaded upon the reduced upper end of bar C and covered by a flat cap M, threaded upon the concentric flange I.

The top H of the pedestal is provided with 85 four radial arms N N and O O ninety degrees apart. On the diametrically opposite arms N N are lugs P P, in which a frame Q is tiltably pivoted. The other arms O O are vertically bored to receive pins R R, which bear 90 under the tiltable frame in opposite directions from its pivots to adjust its inclination, being moved up or down by hand and secured in any adjustment by thumb-screws S S.

Tubes T T are secured to the frame Q, in 95 which are slidably mounted rods U U, provided with hooks to pass over the end of the frame and secure a book in position thereon, the rods being rigidly secured in any adjustment by thumb-screws V.

100

The construction of my invention will be readily understood from the foregoing description, and its operation may be described as follows: The base A being secured to the

counter, desk, or table, any heavy book, such as a hotel-register, may be laid on the tilting frame and secured by the hooked rods U U, when it may be tilted to any desired inclination and secured by the thumb-screws S S and may be turned in any direction, the tilting frame and pedestal rotating on the bushing, the rotative movement being rendered smooth and easy by the ball-bearings.

10 While I have illustrated and described the best means now known to me for carrying out my invention, I do not wish to be understood as restricting myself to the exact details of construction shown, but hold that any slight 15 variation therefrom such as might suggest itself to the ordinary mechanic would clearly be comprehended in the limit and scope of my invention.

Having thus described my invention, what 20 I claim as new, and desire to secure by Letters Patent of the United States, is—

1. In combination, the base, the headed square bar rising therefrom, the bushing

thereon, the pedestal mounted to turn on the bushing having a base carried on the main 25 base by ball-bearings, the top or head of the pedestal, the head screwed on the top of the square bar and supported upon the pedestal-head by ball-bearings, the concentric threaded flange projecting upward from the pedestal-head, and the cap threaded thereon, substantially as described.

2. The combination of the rotatable pedestal, its head provided with radial arms N, N, O, O, the tilting frame pivoted in lugs on 35 arms N, N, the adjusting-pins slidably mounted in vertical openings through arms O, O, and bearing under the tilting frame at opposite sides of its pivots, and the thumb-screws for securing the pins, substantially as de- 40 scribed.

LOUIS ALLEN MAYO.
